UNITED STATES PATENT OFFICE.

MAX GARBELL, OF CHICAGO, ILLINOIS, ASSIGNOR, BY MESNE ASSIGNMENTS, TO
O. D. JENNINGS & COMPANY, OF CHICAGO, ILLINOIS, A CORPORATION OF ILLINOIS.

TYPEWRITER.

Application filed January 31, 1921. Serial No. 441,157.

To all whom it may concern:

Be it known that I, MAX GARBELL, a citizen of the United States, residing at Chicago, in the county of Cook and State of Illinois, have invented a certain new and useful Improvement in Typewriters, of which the following is a full, clear, concise, and exact description, reference being had to the accompanying drawings forming a part of this specification.

This invention relates to improvements in typewriters, and more particularly to a ribbon guide and vibrator therefor.

One object of the invention is to provide a ribbon vibrating mechanism of a simple and efficient construction adapted to elevate the inking ribbon from its lower inoperative position to a higher operative or printing position upon actuation of any of the keys especially in that class of typewriters known as "visible" typewriters.

Another object of the invention is to provide a combined inking ribbon vibrator and guide of the type indicated in the preceding paragraph which is especially adapted for that class of typewriters wherein a plurality of different printing or case positions is utilized, the ribbon always being automatically maintained in definite relations with respect to the printing point on the usual platen, regardless of the relative case or printing positions of the type bars and platen.

Another object of the invention is to provide a combined vibrator and guide for a multi-color inking ribbon of a typewriter so arranged that any one of the colors of the ribbon may be utilized in printing the characters, the combined vibrator and guide being movable from inoperative to operative position upon actuation of a printing key so as to maintain the visible characteristics of the typewriter.

Another object of the invention is to provide a ribbon vibrating mechanism which is adapted to vibrate the ribbon from an inoperative to an operative position upon actuation of a printing key in which predetermined relations are maintained between the ribbon and the platen, in that type of machine where the platen has a plurality of printing positions, the vibrating device being also adapted to provide for shifts of a

multi-color inking ribbon, permitting the use of any color of the ribbon in any printing or case position of the platen.

Other objects of the invention are: to provide a ribbon vibrating device, the position of which will always automatically be controlled in accordance with the case or printing position of the platen; to provide a ribbon vibrating device of the character indicated in any of the preceding objects of the invention which is adapted to be operated by the usual universal bar of the typewriter and in synchronism with the usual escapement mechanism; to provide a typewriter having a ribbon vibrating device in accordance with any of the preceding objects of the invention in which the platen carriage and carriage support are bodily removable from and replaceable on the main frame of the typewriter independently of and without involving the manipulation of any portion of the ribbon vibrating or guiding device on the part of the operator; and to provide a vibrating device characterized in accordance with any of the preceding objects of the invention in which the vibrating device is compact and therefore especially useful on a typewriter of the so-called "portable" type as exemplified in my prior Patent 1,305,893, granted June 3, 1919.

Other objects of the invention will more clearly appear from the description and claims hereinafter following.

In the drawings forming a part of this specification, Figure 1 is a top plan view of a typewriter showing my improvements in connection therewith, a portion of the typewriter being broken away in order to more clearly illustrate certain features of the invention. In this figure the keyboard is omitted. Figure 2 is a vertical, sectional view taken thru the machine and corresponding substantially to the line 2-2 of Figure 1, all of the parts being shown in their normal or inoperative position. Figure 3 is a detail perspective of the ribbon vibrator and guide proper shown disassociated from the rest of the typewriter with the exception of one or two parts as herein-after described and disassociated also from certain cooperating parts carried by the platen carriage. Figures 4 and 5 are enlarged vertical, sectional views correspond-

ing substantially to Figure 2, certain parts being broken away to more clearly illustrate the details of construction, Figure 4 illustrating the normal or inoperative condition 5 of the parts when the platen is in its lowermost printing or case position and Figure 5 illustrating the condition obtaining when the platen is in its uppermost printing or case position. In Figure 5, the dotted lines 10 also indicate the positions assumed by the different parts upon actuation of a type bar. Figure 6 is a front elevational view of the platen and carriage and illustrating more particularly the color shift mechanism. 15 Figure 7 is a detail, sectional view upon an enlarged scale corresponding substantially to the line 7—7 of Figure 6. And Figure 8 is a perspective view corresponding substantially to Figure 3 but illustrating another 20 embodiment of the invention, parts being broken away in Figure 8 in order to accommodate the figure on the sheet.

In said drawings, the main frame of the machine is indicated at 10, the same being 25 of any desired form suitable to accommodate the various other parts of the typewriter. In the typewriter to which I have shown my invention applied, I employ a plurality of radially arranged, reciprocating 30 or trust type bars 11, each of which carries at its inner end a vertically extending type block 12 having a plurality of printing type characters 13^a, 13^b and 13^c thereon arranged in a vertical series and spaced from 35 each other, the lower characters 13^a preferably being the lower case characters, the intermediate characters 13^b being the upper case or capitals and the topmost characters 13^c being numerals and punctuation marks, etc. Each type bar 11 carries a horizontally 40 extending rack 14 at its front or outer end with which is adapted to engage a segmental gear 15 pivoted as indicated at 16 to a portion of the main frame, the segmental gear 45 being adapted to be oscillated by means of a link 17 attached to a lever arm 18 at one end and to a key lever 19, the latter being fulcrumed at its inner end as indicated at 20 to a common fulcrum bar 21. For a 50 more detailed description of the type bar action reference may be had to my said prior Patent 1,305,893 and for the details of the type block reference may be had to my pending application, Serial No. 420,892, filed November 1, 1920. The type blocks are adapted 55 to slide upon a table 22 in reciprocating to and from printing position, being suitably centered at the extreme inner end of their movement by a guide 23. As is customary, I provide a universal bar 24 pivotally 60 mounted on the main frame of the machine as by the pivot rod 25. A spacer key of lever type is indicated at 26, the same being fulcrumed as indicated at 27 to a suitable 65 bracket carried by the main frame of the

machine, a spring 28 reacting against the spacer key to normally influence it toward the position indicated best in Figure 2.

In the type of machine which I have illustrated, the platen is adapted for vertical movement or case shifting relative to the type bars, the platen being indicated at 29. Said platen is rotatably mounted in any suitable manner on a platen carriage 30 which is adapted for reciprocating or longitudinal movement transversely of the machine by means of rails 31—31 forming a part of said carriage and cooperating rails 32—32 rigidly carried by a carriage support 33, there being a plurality of anti-friction 75 balls 34 interposed between the sets of tracks 31—32 to reduce friction. As will be understood by those skilled in the art, a suitable escapement mechanism is employed to effect the step by step movement of the 80 platen transversely of the machine, such escapement mechanism not being shown as the same is deemed unnecessary for an understanding of my invention. The carriage 85 30 and carriage support 33 together constitute what may be termed the combined platen carriage support and carriage, and said combined carriage support and carriage, as an entirety, is vertically movable or shiftable relative to the main frame 90 of the machine. To provide for this movement, the carriage support is provided with vertically extending enlargements 35—35 near each end thereof, the same being vertically axially recessed so as to telescope on 95 a corresponding pair of upstanding posts 36—36 carried by the main frame of the machine. In addition to the vertical case shift movement provided for, the combined platen support and carriage is readily bodily 100 vertically removable from the main frame of the machine. Although I have not herein shown any case shifting means, as the same are not deemed essential to an understanding 105 of the present invention, a satisfactory form 110 of such means permitting of the case shift and removable features above enumerated, is disclosed in my pending application 360,958, filed Febr. 24, 1920, to which reference may be had.

Referring now more particularly to the ribbon vibrator and guide, I have shown a multi-color inking ribbon 37 having an upper portion 37^a of one color and a lower portion 37^b of another color. Said ribbon extends crosswise of the machine in a well known manner and is wound and unwound at its ends on reels 38—38 mounted on the frame of the machine, the ribbon being fed by any suitable means, not shown. The ribbon guide proper and vibrator is best shown in Figure 3, where it will be seen that I employ two vertically elongated loops 39—39, each having an opening 40—40 to permit the insertion and removal of the ribbon and, 120 125 130

after it is once inserted, the ribbon will be held vertical and unwrinkled, as shown in Figures 2, 4 and 5. The loops 39 are each provided with downwardly extending bars 41—41 each of said bars 41 having an enlargement as indicated at 42, at which point is secured a laterally extended cylindrical pin 43, for the purpose hereinafter described. The bars 41 are vertically guided by any suitable means, that which I have shown comprising a plate 44 secured at its upper end to a part of the main frame 110 and at its lower end hooked under a fixed bracket or plate 45 and a supplemental plate 46 secured to said part 110 of the main frame by a machine screw 47 or other equivalent means. The plate 44 at its upper end has outturned flanges 48—48 at each side thereof and the plate 46 has cooperating right-angled flanges 49 at each side, the two sets of flanges 48 and 49 together forming substantially rectangular vertically extending guiding openings for the bars 41. Near the bottom of the plate 44, the same is so stamped as to provide a pair of horizontally and rearwardly extended flanges 50—50, each of which is slotted in alinement with the aforementioned upper guides so as to guide the bars 41 at their lower ends. The plate 44 is also preferably provided with integral upwardly and inwardly extended bracing bars 44^a—44^a which, at their upper ends, are hooked over the universal fulcrum 21 as indicated at 44^b in Figure 2. Altho the ribbon guide proper is formed of two separate elements 39—41, as just described, for convenience, the same is referred to hereinafter as a single element or ribbon guide proper. Secured to another part 210 of the main frame at the same horizontal level as the part 110 but in front thereof, is a stamped plate bracket 51 having a pair of laterally spaced depending arms 52—52. Said bracket may be secured by the machine screw 54 and in order to prevent the bracket from twisting where only one securing screw is employed, the bracket may be provided with horizontally disposed flanges 55—55 extending under the part 210 of the main frame. A horizontally extending fulcrum or pivot pin 56 is mounted in said arms 52 near the bottom thereof. Pivots mounted on the pin 56 is a yoke-like or U-shaped lever having parallel side arms 57—57 connected at their outer end by a cross piece 58. Pivots connected to the outer end of said lever 57—58 as indicated at 59, is another yoke-like lever 60 having a pair of spaced arms 61—61 which are curved at first downwardly and then inclined at their lower ends indicated at 62—62, said arms straddling the bars 41 of the ribbon guide and vibrator. The lower ends of each of said arms 61 are formed with elongated slots 63—63 in which extend the studs 43 so as to provide a pivotal but sliding connection between the arms 61 and the ribbon vibrator guide. The lever 61—61 is also provided on one side thereof with a forwardly or outwardly extended lever arm 64 which carries a pivot bolt 65 extending thru a slot 66 in a bell crank lever 67, thereby providing an adjustable pivotal connection between said bell crank lever 67 and the yoke lever 61—61. The bell crank lever 67 is pivotally attached as indicated at 68 to a depending arm or bracket of the main frame. A coil spring 69 is mounted on the pivot pin 68, said spring having one end thereof, 70, hooked under one arm of the bell crank lever, the other end of the spring engaging the bracket 68, so that the spring 69 normally tends to elevate the arm 67^a of the bell crank lever. The other arm 67^b of the bell crank lever which is extended in a general downward direction has pivotally secured thereto at its lower end as indicated at 70, one end of a link 71 which is extended to and operatively connected with a suitable part of the escapement mechanism so as to actuate the latter, such escapement mechanism not being shown as the same is deemed unnecessary. The outer or forward end of the arm 67^a of the bell crank lever is pivotally connected to a link 72 which is extended downwardly and has an adjustable connection with the universal bar 24. In normal condition of the parts, it will be noted that the pivotal connection 65 between the bell crank lever and the arm 64 of the yoke lever 61—61 is substantially in alinement with the pivot pin 56 so that, when said pivot pin 65 acts as a fulcrum for the yoke lever 61 as the latter is bodily vertically adjusted in accordance with adjustment of the yoke lever 57—58 about its fulcrum 56, as hereinafter described, the relative positions of the pivot pins 56 and 65 will not be disturbed.

The yoke or U-shaped lever 57—58 at its inner end has rigidly or integrally formed therewith a centrally disposed arm 73 which is curved first downwardly as indicated at 73^a, then slightly inclined downwardly from the horizontal for a distance as indicated at 73^b and finally is extended upwardly as indicated at 73^c and formed with a generally horizontally disposed shoulder or stop 74. The end 73^b is centered and guided in a slot 75 formed in a downwardly inclined triangular shaped section 46^a of the plate 46. To permit the arm 73 to extend thru the plate 44, the latter is suitably cut away as indicated at 44^c. A tension spring 76 is secured at its upper end as indicated at 77 preferably to the inner end of the screw 54 and at its lower end as indicated at 78 to the cross piece 58 of the yoke lever 57—58, said spring 76 acting to elevate the outer end of the yoke lever 57—58 so far as it is permitted to do so.

Referring now more particularly to Fig.

ures 2, 4, 5 and 6, it will be seen that I have mounted on the platen carriage support near the center thereof and on the forward side, a bell crank 79 pivoted on a screw 80. The lower arm 79^a of said bell crank is formed with a shoulder 81 so positioned that it is adapted to aline and engage with the shoulder 74 heretofore described. The shoulder 81 is so positioned that, when the bell crank 79 is in the full line position shown in Figure 6 and the platen carriage is in its lowermost printing position, as shown in Figures 2 and 4, the stop or shoulder 74 will be depressed to its lowermost normal position as shown in Figure 4 and so that the uppermost section 37^a of the ribbon will be the one which is employed in the operation of the machine, it being observed that the ribbon is below the normal printing position for the lower case type characters as shown in Figure 4 so that the typewritten matter is visible, as will be understood by those skilled in the art. As the platen carriage is given a case shift to either the intermediate or uppermost type character level, it is evident that the stop shoulder 81 of the bell crank 79 will be elevated correspondingly, thereby permitting the tension spring 76 to elevate the free end of the lever 57-58 and correspondingly the pivotal connections 59 of the yoke level 61 which in turn elevates the ribbon vibrator guide so that the latter always maintains predetermined relations with respect to the platen and point of printing.

In order to adjust the inking ribbon to employ a different color section thereof, as for instance the lower color section 37^b, the bell crank 79 is adapted to be manually set or adjusted by means of a rod 82 pivotally connected to the arm 79^b of the bell crank as indicated at 83. Said rod 82 is slidably supported at its lefthand end as viewed in Figure 6 on the carriage support 33 by means of a stud 84 extending thru a slot 85 in said rod. The rod 82 at its end has a depending finger piece 86 by which it may be pushed in or out as will be understood. Where a two-color ribbon is employed, the rod 82 and bell crank 79 will have two adjusted positions and in order to more easily determine these positions without any particular care on the part of the operator and maintain them in either of said positions, said slot 85 is preferably formed with two circular enlargements 85^a-85^b at each end in which is adapted to frictionally engage a conical plug 87 slidably mounted on the stud 84 and yieldingly impelled inwardly by means of the spring 88 which reacts against said block at one end and against the head of the stud 84 at its opposite end. By shifting the bell crank 79 from its full line position to dotted line position shown in Figure 6, the stop or gauge shoulder 74 will be permitted to correspondingly rise as best indicated in Figure

6, thereby permitting elevation of the ribbon vibrator guide a sufficient amount to bring the lower part 37^b of the ribbon in proper position to be struck by the lower case keys. Case shifts of the platen carriage will maintain the relations of the ribbon and platen even with the bell crank 79 shifted to dotted position, as will be understood.

From the preceding, it will be seen that the ribbon vibrator guide rises and falls in accordance with the platen and that the particular color section of the ribbon desired may be determined by setting the bell crank 79. When one of the keys or spacer is actuated, the universal bar 24 will be depressed in a wellknown manner, thereby depressing the arm 67^a (see Figure 3) of the bell crank 67 and thru the intermediary of the yoke lever 61-62, will vibrate or elevate the ribbon guide to inking position. Simultaneous with the operation of the universal bar and the bell crank 67, the escapement mechanism will also be operated as previously described, thru the intermediary of the link 71. Due to the alinement of the pivot pins 56 and 65, heretofore mentioned, which will always obtain regardless of the case position of the carriage or the color section of ribbon being employed, the throw or oscillation of the yoke lever 61-62 will remain the same so that the various adjustments and conditions provided for in the ribbon vibrator do not affect the throw or movement of the ribbon itself, a very important consideration in this type of mechanism.

Due to the unavoidable variations which may occur in the manufacture of the various parts and assembly thereof, certain adjustments may be necessary and particularly is this true with respect to the usual escapement mechanism. Inasmuch as my improved ribbon vibrator and the escapement mechanism are actuated from a common member, the universal bar 24, adjustment to take care of variations in the escapement mechanism might effect the throw of the ribbon vibrator guide unless special means are provided to permit independent compensation with respect to the vibrating mechanism. To this end, each of the keys 19 and spacer lever 26 may be formed with a slotted enlargement as indicated at 26^a in Figure 2, where engagement is obtained with the universal bar. This permits the lower engaging edge of the key lever or spacer lever to be readily adjusted by either squeezing with a pair of pliers or by spreading with a screw driver or the like, inserted thru the slot.

In Figure 8, I have shown a different method of compensating for the variations and adjustments mentioned in the preceding paragraph which provides for a quicker adjustment than in the case of the structure illustrated in Figure 2 although the lat-

ter may have a slight advantage in the cost of manufacture. The embodiment shown in Figure 8, is distinguished, broadly, from the embodiment shown in Figure 3, by utilizing an adjustable connection between the parts of the lever which are directly interposed between the universal bar operated bell crank 67 and the ribbon vibrator guide proper. In Figure 8, 164 corresponds to the 5 arm 64, the same being pivoted as indicated at 159 to the yoke lever 157—158. The downwardly dependent arms 161—161 which are connected by an integral cross piece 161^a as in the case of Figure 3, are independently pivoted on the pin 159 so that 10 relative pivotal movement between the lever arm 164 on the one hand and the arm 161 on the other hand is permitted. This relative pivotal movement is governed by a tension spring 89 attached at one end to an upstanding finger 164^a and at its other end to an upstanding finger 161^c. The lever arm 164 is provided with a stamped integral flange 164^b in which is mounted an adjustable screw stop 90 adapted to engage 15 with a finger 161^b formed integrally with the cross piece 161^a. Said finger 161^b is also adapted to cooperate with another adjustable screw stop 91 threaded in a flange 157^a formed integral with the yoke lever 157—158. The cross piece 158 has formed integrally therewith at its center an arm 173 corresponding to the arm 73—74 of the structure shown in Figure 3, the position 20 of which is determined in accordance with the position of the stop 81 carried by the platen carriage support.

With the construction illustrated in Figure 8, it is evident that the position of the yoke lever 157—158 will be governed the same as in the case of the yoke lever 57—58. Adjustment of the universal bar, as for instance to take care of changes necessary in the escapement mechanism, will in turn affect the lever arm 164. When said adjustment has been obtained, the screw stop 90 is then adjusted so as to engage the finger 161^b and thereby properly position the lever arm 164 and bring its pivotal connection (corresponding to 65) with the bell crank lever (corresponding to 67—67^a—67^b) in alignment with the pivot or fulcrum (corresponding to 58) of the yoke lever 157—158. The adjustable screw stop 91 is then 25 adjusted to such a position that it will be engaged by the finger 161^b when the ribbon guide and lever arms 161 have been moved to their operative or printing position. It is evident that, upon depression of the universal bar and consequent depression of the lever arm 164, the lever arms 161 will follow the movements of the lever arm 164 under the tension of the spring 89 to thereby elevate the ribbon vibrator guide until the latter has reached its permitted uppermost

position when further movement is prevented by engagement of the finger 161^b with the adjustable screw stop 91.

From the preceding description, it will be seen that, with my improvements, all possible conditions with respect to the relative positions of a multi-color ribbon and the platen are automatically taken care of with the exception of the manually set means utilized in the color positioning stop. It will furthermore be observed that removal of the platen and the combined platen carriage and carriage support bodily from the main frame of the machine does not require any manipulation of the operator to effect disconnection of any parts relating to the ribbon vibrator and guide but on the contrary the platen and the combined carriage and carriage support may be removed and replaced at will and the proper relation of the ribbon vibrator with respect to the platen will always be maintained.

I have herein shown and described what I now consider the preferred manner of carrying out the invention, but the same is by way of illustration only and not by way of limitation. I am aware that various changes and modifications may be made in the details of construction and arrangement of parts and all such changes and modifications that come within the scope of the claims appended hereto are contemplated.

I claim:

1. In a typewriter having a main frame, a platen, platen carriage, carriage support, type bars provided with a plurality of spaced printing type characters thereon, means for effecting a relative case shift between the type bars and the platen to accord with different printing positions, and an inking ribbon: the combination with a ribbon vibrator; of a vibrator lever; a support pivoted to the main frame and to which the vibrator lever is pivoted, said support being automatically positioned in accordance with the relative case shift positions of the platen and type bars; an operating lever pivotally connected to the vibrator lever, the pivotal axis of said operating lever being substantially in alignment with the pivotal axis of said support whereby the relative normal positions of the vibrator and platen remain substantially constant in all case shift positions; and means for actuating said operating lever.

2. In a typewriter having a main frame, a platen, platen carriage, carriage support, type bars provided with a plurality of spaced printing type characters thereon, means for effecting a relative case shift between the type bars and the platen to accord with different printing positions, and an inking ribbon: the combination with a ribbon vibrator; of a vibrator lever; a support

means for actuating said operating lever; and manually set means for varying the normal position of the vibrator to thereby present different portions of the ribbon for printing, said manually set means being mounted on the platen carriage support.

9. A ribbon vibrator for a typewriter having a main frame, said vibrator including: a fulcrum lever pivotally mounted about a fixed pivot at one end; a tension spring extending between said fulcrum lever and the main frame; a vertically movable ribbon vibrator; a second lever pivotally mounted adjacent the free end of said fulcrum lever, said second named lever having operative engagement with the ribbon guide and adapted to impart vertical movement to the latter; a third lever pivotally supported from a fixed portion of the frame and adapted to be oscillated upon actuation of the usual universal bar, said third lever having pivotal connection with the second named lever substantially in alinement with the fixed pivot of the fulcrum lever; and a stop shoulder carried by said fulcrum lever and rigid therewith, the position of said shoulder and fulcrum lever being adapted to be determined by the case printing position of the typewriter platen.

10. A ribbon vibrator attachment adapted to be attached to the main frame of a typewriter, said attachment comprising: a bracket adapted to be secured to a rigid part of the typewriter frame, said bracket carrying a relatively fixed pivot; a vibrator guide adapted to be secured to another part of the typewriter frame; a vibrator vertically slidably mounted in said vibrator guide; a fulcrum lever pivotally mounted at one end on said fixed pivot; a stop shoulder rigid with respect to said fulcrum lever and the position of which is adapted to be determined by a cooperating member carried by the platen carriage support; and a lever pivotally mounted intermediate its ends adjacent the free end of said fulcrum lever, said second named lever having operative engagement with the ribbon vibrator to effect vertical movements of the latter, the opposite end of said second named lever being adapted

for pivotal connection to means operated from the usual universal bar of the typewriter.

11. In a typewriter, the combination with the main frame, type printing bars, universal bar, operating keys, platen, platen carriage, carriage support, and inking ribbon, of a lever pivotally supported from a part of the main frame and operatively connected at one end to the universal bar and at its other end to a link adapted to actuate an escapement mechanism; of a combined ribbon guide and vibrator proper, adjustable to different operating positions to bring different zones of the ribbon in cooperative relation to the type of the bars; means for imparting vibratory movement to said vibrator proper in its different operating positions and operable from said first named lever; means for determining the normal inoperative position of said last named means in accordance with the case-printing position of the platen; and adjustment means determinative of the different operating positions of said vibrator guide and also determinative of the normal position of the actuating means for each operative position of the vibrator guide with respect to the universal bar independently of the relation between the said escapement link actuator and the universal bar.

12. In a typewriter, the combination with a main frame; of a platen, a platen carriage, and a carriage support; a universal bar; a combined vibrator and guide for a multi-color inking ribbon supported from the main frame and operable from the universal bar from inoperative to operative position upon movement of the universal bar; and an adjustable stop on the carriage support, said stop being in continuous engagement with the combined vibrator guide in all positions thereof to determine the normal position of the latter with respect to the platen in accordance with the particular color of the ribbon desired for use.

In witness that I claim the foregoing, I have hereunto subscribed my name this 12th day of January, 1921.

MAX GARBELL.
